FIG. 2

Inventor:

Thomas W. Loaring
by A. S. Daivener,
Attorney

UNITED STATES PATENT OFFICE.

THOMAS W. LOARING, OF CLEVELAND, OHIO, ASSIGNOR TO THE CUYAHOGA TELEPHONE COMPANY, OF SAME PLACE.

SIGNALING APPARATUS FOR TELEPHONE-STATIONS.

SPECIFICATION forming part of Letters Patent No. 670,408, dated March 19, 1901.

Application filed October 27, 1900. Serial No. 34,589. (No model.)

To all whom it may concern:

Be it known that I, THOMAS W. LOARING, a citizen of the United States of America, and a resident of the city of Cleveland, State of 5 Ohio, have invented certain new and useful Improvements in Signaling Appliances for Subscribers' Telephone-Stations, of which the following is a specification.

My invention relates to improvements in 10 signaling apparatus, and more particularly to improvements in apparatus designed for sending selective signals from the subscriber's station of a telephone system, the object of my invention being the provision of simplified 15 and reliable calling appliances for the subscribers' stations which are adapted to actuate responsive signal-receiving apparatus at the central office.

In a telephone system now in common use 20 the selective calls or signals are sent to the central office through the medium of magneto-generators or induction-coils, which being associated with switch mechanism of some-what complex character may be caused to 25 transmit the signaling-current to associated polarized relays disposed at the central office, the said relays being adapted alternatively to be actuated by such currents. The mechanism hitherto employed for effecting the trans- 30 mission of the requisite signaling-currents has necessitated the employment of a large number of switch-contacts, which in practice have been found frequently to get out of order, ren- 35 dering the subscriber's station apparatus tem- porarily inoperative. The switch-contacts, moreover, were found not infrequently to re- main abnormally closed, thereby short-cir- 40 cuiting the signaling-battery when the same was employed and rendering its renewal nec- essary. The apparatus of my invention is materially simplified, the number of contact parts being greatly reduced, while difficulties developed in the use of prior apparatus are entirely obviated.

45 I will describe my invention in its preferred embodiment as applied to a telephone call-box for the subscriber's station, wherein a battery and induction-coil in connection with the simplified switch mechanism of my in- 50 vention are employed for transmitting the calling-currents from the subscriber's station.

Briefly described, my invention consists, as stated, of a simplified switching mechanism which is adapted to throw the employed source of electrical energy into circuit with 55 selective signal-receiving apparatus in such manner that the proper signal will be received at the central office. An electrically-actuated apparatus in the nature of a relay device is employed for connecting the call ap- 60 pliance with the external circuit.

My said invention will be more readily un- 65 derstood by reference to the accompanying drawings, forming a part of this specification, in connection with which I will set forth 70 more particularly the construction and oper- ation of the preferred embodiment of the in- vention.

Figure 1 of the drawings illustrates a sub- 75 scriber's telephone call-box equipped in ac- cordance with my invention, the call-box be- ing shown open and a small portion of the apparatus being broken away more clearly to illustrate the construction. Fig. 2 is a dia- 80 gram setting forth the circuit arrangement of 75 the telephone call-box and indicating as well the signal-receiving apparatus at the central office, and Fig. 3 is a detail view illustrating the reversing-switch mechanism.

The same characters of reference are em- 85 ployed in the several figures of the drawings to indicate the same part or parts.

The telephone call-box of Fig. 1 is equipped 90 with the usual local battery *b*, which, in con- nection with the induction-coil *d e*, serves to 95 transmit signaling-currents of high potential over the external circuit to the selective sig- naling-drops or polarized annunciators *f g*, *h*, and *i*, disposed at the central office. These latter we may consider as being upon differ- 100 ent sections of a telephone-switchboard, as is required in a well-known system of telephony.

Associated with the induction-coil and bat- 105 tery are a number of switch-contacts *a c m*, and *r*, adapted, respectively, to be operated by the corresponding push-buttons *A C M*, and *R*, mounted upon and having plungers extending through the lid of the call-box. A polarized call-bell *j* is also placed upon the lid of the box, by which signals may be re- 110 ceived at the subscriber's station in the usual manner. Supported upon the switch-hook *k*

is seen the telephone-receiver *l*, which normally maintains the calling-circuit closed within the box.

In the upper portion of the call-box are seen two relays *n* and *o*, which normally maintain one side of the line open, the latter relay also controlling the circuit through bell *j*, which is normally closed.

In order to simplify the description, the talking-circuits and the switching operations effected by the telephone-hook are not set forth herein, since they contain no features of novelty.

It will be seen that the contact-springs *a* and *r* when depressed are adapted to close circuit directly with a common contact-strip *p*, which we will assume is connected with the negative pole of battery *b*. Upon depressing contact-spring *c* or *m*, however, their extended ends, the former being broken away and shown only in dotted lines, will first engage an upwardly-extending insulating-stop *q*, carried upon spring *s*. Springs *s* and *t* are normally maintained in contact; but they are caused to separate by the depression of the spring *c* or *m*, spring *s* being carried downward into engagement with strip *p*. At this time the extended end of spring *c* or *m* is also brought into electrical contact with spring *t*. The depression of any of the springs *a*, *c*, *m*, or *r* through the agency of their respective push-buttons serves to close the battery-circuit through the induction-coil and actuate one or other of the relays. The relay *n* is energized by pressing button *A* or *C* and will establish connection with the left-hand line *x* of the external circuit appearing at binding-post *u*. This is accomplished by the action of its L-shaped armature, which serves to engage contact-spring *n'* with its coacting spring *n''*. The relay-armature, it will be seen, is loosely held in position by a screw at the end of the relay, upon which it is free to rock under magnetic influence. Similarly relay *o* is energized upon pressing button *M* or *R*, thus serving to establish connection with the external grounded circuit between springs *o'* and *o''* and also, as explained, opening the normally closed bell-circuit between springs *o''* and *o³*, which otherwise would short-circuit the calling-current within the box. The secondary winding *e* of the induction-coil is connected between one side *y* of the line and the normally open relay-contacts *n'* and *o'*. Binding-post *w* is connected to ground and with relay contact-spring *o''*.

Quite obviously the circuits of the telephone-call-box could be but imperfectly set forth upon Fig. 1, and accordingly Fig. 2 will be referred to in order that I may make clear the arrangement and operation of said device.

The annunciators *f* and *g* are connected between the limbs *x* and *y* of the line and are adapted respectively to be actuated by currents of negative and positive polarity. Similarly the annunciators *h* and *i* are con-

nected in a branch *z* between line *y* and ground and may be alternatively operated by currents of opposite polarity. These currents are generated in the secondary *e* of the induction-coil, which, however, it must be remembered, is normally upon open circuit. Assuming then that the annunciator *f*, which to carry out the illustration we will say is disposed upon the A section of the switch-board and is to be actuated, the subscriber will depress button *A* and contact-spring *a* will be engaged with strip *p*, closing the circuit of battery *b* through the primary *d* of the induction-coil. Circuit may be traced from the negative pole of the battery by conductor 1 to relay *n*, conductor 2, contacts *a* *p*, winding *d*, from left to right, conductor 3, contacts *s* *t*, and conductor 4 to the positive pole of the battery *b*. The relay is excited to attract its armature, which closes the line-circuit *x* between contacts *n'* and *n''*. Upon releasing the button *A* the circuit is abruptly broken and current of high potential is generated in the secondary *e* and transmitted to line *x* *y*, thus serving to throw the drop *f* and signal the operator at board A. The relay is sufficiently sluggish in its action to permit the passage of the signaling-current before the line-circuit is opened. Pressing the C button, it will be seen, serves to send a current of opposite polarity over the same circuit to operate drop *g*. Thus the circuit may be traced from the battery through relay *n*, conductors 2 and 5, springs *c* and *t*, conductor 6, winding *d*, from right to left, strip *p*, spring *s*, and conductor 4 to the battery. The separation of springs *s* *t*, effected in the manner described by actuating either of the contact-springs *c* or *m*, which are provided with laterally-extending ends, serves to reverse the flow of the current in the winding *d* with a corresponding reversal of the resulting signaling-current. When the buttons *R* or *M* are pushed, similar circuits are established through the relay *o*, which is actuated to open the grounded bell-circuit and simultaneously close the circuit between conductor *y* and grounded binding-post *w*. It will not be necessary, it is thought, to trace these circuits step by step, since the polarized annunciator *i* or *h* is operated in the same manner as is annunciator *f* or *g*.

The apparatus employed in my improved call-box, it will be seen, is greatly simplified as compared with that hitherto devised. By this construction I am able to effect the necessary circuit changes with one-third the number of contact parts previously required and also insure the requisite opening of the line and bell circuits.

That my invention is susceptible of other applications and of modifications not herein described will be apparent to those skilled in art. I have merely set forth the same in this specification in its preferred form.

I therefore claim, and desire to secure by Letters Patent, the following:

1. In a call-box for subscribers' telephone-stations the combination with a source of electrical energy, of a plurality of switches *m*, *r*, *s* and *t* controlling said source of energy, whereby selective signals may be transmitted, and a relay *o* associated therewith controlling the continuity of the line-circuit, substantially as described. 5
2. In a call-box for subscribers' telephone-stations the combination with a source of electrical energy of a signal-sending induction-coil associated therewith, a plurality of switches *m*, *r*, *s* and *t* controlling said source of energy, whereby selective signals may be transmitted, and a relay *o* associated therewith controlling the continuity of the line-circuit, substantially as described. 10
3. The combination in apparatus of the class described, with a signal-generating coil, of a plurality of signal-sending switches, a source of electrical energy adapted to be connected by said switches with the said coil, and electromagnetic apparatus adapted to complete the line-circuit when the flow of current is established in the said coil, substantially as described. 15
4. In apparatus of the class described, the combination with a local battery *b* of a signaling-switch *r* controlling the flow of current from said battery, a signal-sending coil *d*, *e*, associated therewith, whereby selective signals may be transmitted, a signal-receiving device *j*, and a relay *o* controlling the circuit continuity of the line and of the signal-receiving device, substantially as described. 20
5. In a signaling appliance for subscribers' telephone-stations the combination with a plurality of signaling-switches for sending separate selective signals, of a reversing-switch associated with a portion of said signal-sending switches and adapted to be actuated thereby, electromagnetic apparatus constituting a source of electrical energy for sending signals, 25
- associated with said switches, and a relay device adapted to close the signaling-circuit 45 when the signal-sending switches are operated, whereby the appropriate signal-receiving device connected with said appliance may be actuated, substantially as described.
6. In a call-box for subscribers' telephone-stations the combination with a plurality of signal-sending switches as *a*, *c*, *m* and *r*, for sending separate selective signals, of a reversing-switch *s*, *t* associated with switches *c* and *m* and adapted to be actuated thereby, 50 an induction-coil *d*, *e*, a source of electrical energy and relays *n* and *o* adapted alternatively to close separate signaling-circuits when the signal-sending switches are operated, whereby the appropriate signal-receiving device connected with the call-box may be operated, substantially as described. 55
7. In a signaling appliance for subscribers' telephone-stations the combination with a plurality of signal-sending switches for sending 60 separate selective signals, of a reversing-switch associated with a portion of said signal-sending switches and adapted to be actuated thereby, an induction-coil, a battery adapted to be connected therewith, a subscriber's call-bell and a plurality of relays adapted alternatively to close separate signaling-circuits through the secondary winding of the induction-coil, and to remove the subscriber's call-bell from circuit when the 65 signal-sending switches are operated, whereby the appropriate signal-receiving device connected with said signaling appliance may be actuated, substantially as described. 70
- Signed at Cleveland, Ohio, this 24th day of October, 1900. 80

THOS. W. LOARING.
